ARCHIE MACPHAIL NIVEN, OF DETROIT, MICHIGAN, ASSIGNOR TO CONTINENTAL MOTORS CORPORATION, OF DETROIT, MICHIGAN, A CORPORATION OF VIRGINIA

INTERNAL-COMBUSTION ENGINE

Original application filed March 7, 1927, Serial No. 173,320. Divided and this application filed December 7, 1927. Serial No. 238,248.

This invention relates to internal combustion engines and more particularly to the sleeve valve type of engine. In this general type of engine it is customary and desirable to provide the fuel intake at the side of the engine opposite to the exhaust outlet. Therefore difficulty has been experienced in providing efficient and at the same time compact and well appearing apparatus for heating the intake manifold or intake gases at one or more points by the exhaust gases. It has been customary to locate the exhaust manifold and intake manifold on opposite sides of the engine and then extend a pipe, ordinarily branched from the exhaust manifold, either around the engine block or else arched above the engine block whereby some of the exhaust gases are conducted to the intake manifold to form one or more so-called hot spots for heating the intake gases to form the desired mixture. Such prior devices are quite inefficient since the exhaust gases do not pass directly to the intake manifold; furthermore the provision of the branched exhaust pipe around or above the cylinder block destroys to a considerable degree the otherwise attractive and pleasing appearance of this type of engine besides adding to the complexity of the engine.

My invention has among its objects the provision of means for overcoming the aforesaid objectionable characteristics of sleeve valve engines. I have provided a construction whereby a portion of the exhaust gases may be conducted directly to heat the intake manifold, affording a simple apparatus, of high efficiency, and at the same time preserving the neat appearance of the engine.

A further feature of my invention resides in utilizing one or more sleeve intake ports of a sleeve valve engine to serve as gas exhausting means. One useful purpose of such an arrangement resides in conducting exhaust gases through sleeve intake port or ports for heating the intake gases at a convenient point.

This application is a division of my co-

pending application Ser. No. 173,320, filed March 7, 1927.

With the foregoing and other objects in view my invention provides a novel combination and arrangement of parts more particularly hereinafter described and claimed.

Referring to the drawings illustrating one embodiment of my invention,

Fig. 1 is a sectional elevation view through an engine cylinder,

Fig. 2 is a top plan view of the engine partly in section along 2—2 of Fig. 1,

Fig. 3 represents, diagrammatically, a development of the sleeve and cylinder ports.

In the drawings reference character A represents the engine block having one or more cylinders 10, the intake charge passing from intake manifold B to the cylinders and from the cylinders to the exhaust manifold C being controlled by one or more valves 11 controlling suitable ports. In the drawings I have illustrated my invention in connection with an engine of the single sleeve valve type, in which the sleeve is ordinarily driven at half engine speed by a suitable mechanism usually including a valve lay shaft (not shown) to impart to the sleeve a combined movement axially and circumferentially of the sleeve, i. e., a combined reciprocating and oscillating movement whereby a point on the sleeve will trace a closed figure on the cylinder. Such mechanisms for imparting such a motion to the sleeve are well known in the art.

The intake manifold B is formed with the usual carburetor connection 12, the gases being divided at 13 into branches 14 and 15 having outlet passages 16 leading to the various cylinders 10. Around the T-connection 13 I have located a casing or jacket 17 having one or more exhaust gas inlet openings 18 communicating with one or more conduits 19^a leading to a convenient cylinder or cylinders. As shown, I prefer to form the conduit 19^a in the form of a passage through the cylinder block A. The exhaust gases from openings 18 circulate around the T-connection 13, whence they pass through outlet 20 and the passage 21, also preferably extending through the cylinder block, to the

inlet point 22 of the exhaust manifold C. Baffles 23 may be located between inlets 18 and outlet 20 or at other desired points to insure proper circulation of exhaust gases in the heating jacket 17.

The exhaust manifold C may be of any well known or other preferred type. I have illustrated this manifold as having the main longitudinal exhaust chamber 24 into which the exhaust gases pass by conduits 25 from the various cylinders, 26 being the exhaust pipe outlet.

The flow of auxiliary gases from one or more working cylinders may be controlled as follows. Referring to Figs. 1 and 3 I have shown one customary arrangement of intake and exhaust ports, the sleeve ports in Fig. 3 being shown in full lines and the cylinder ports being shown in broken lines. The exhaust ports of the sleeve and cylinder are designated "Ex" while the intake ports are designated "In". The sleeve travel with respect to the cylinder is indicated at 27. In carrying out my invention I utilize one or more of the usual sleeve intake ports 28^a to exhaust a portion of the exhaust gases to the cylinder passage 19^a leading to the intake manifold heating jacket 17 as shown in Fig. 2. The usual cylinder intake and exhaust passages 29 and 30 respectively communicate with the intake and exhaust passages 16 and 25. With reference to Fig. 3 it will be noted that the cylinder is being exhausted in the usual manner except that the passageway 19^a is located so as to conduct a portion of the exhaust gases by way of one or more of the then otherwise inactive sleeve valve ports 28^a. At such time during the cycle when intake, compression, or firing occurs, the passageway 19^a is inactive, this opening being so located as to provide the necessary seal preventing leakage at such times. Thus simple means is provided for conveniently supplying any desired portion of the exhaust gases toward the intake manifold from the side of the cylinder substantially adjacent the intake manifold.

My invention is not limited in its scope to any particular construction or arrangement of valves, since whether the valves are of the rotary, reciprocating, combined reciprocating and oscillating (as illustrated), single or multiple sleeves, is relatively unimportant as is the particular manner of driving the sleeves. Furthermore the details of the arrangement for applying the heat of the exhaust gases to the intake manifold may likewise vary, since it may be preferred to subject one or more portions of the pipe conducting the intake gases to more or less intimate or remote contact with the heating surface instead of jacketing the branch of the manifold as I have shown for purposes of illustration. A further modi-

fication within the scope of my invention might be made in the construction of the exhaust manifold and the point or points of introduction of the auxiliary exhaust gases into the main exhaust line of travel. If desired, instead of returning the exhaust gases, which are directed to form the hot spot, back to the exhaust manifold, the passageway 21 may be dispensed with and such auxiliary exhaust directed to other points of disposal, such as directly to the atmosphere by removal of the plug 31 as the quantity of auxiliary exhaust gases would ordinarily be comparatively small.

One important feature of my invention resides in providing means for passing exhaust gases directly to heat the intake gases in an engine of the sleeve type wherein the exhaust and intake cylinder ports are ordinarily arranged so as not to permit a convenient hot spot construction whereby I am enabled to obtain the benefits of an efficient fuel mixture commonly incorporated in the ordinary poppet valve, and other types of engines having the intake and exhaust manifold conveniently located on the same side of the cylinder block. Furthermore I avoid unattractive and inefficient transfer pipes for conducting the exhaust gases, after they leave the cylinder, to an intake manifold located remotely such as on the side of the cylinder block opposite the exhaust manifold.

It will be noted that in Fig. 3, the sleeve port marked "In-Ex" is what is commonly known as a double purpose port in that it functions both as an exhaust and an intake port, while the remaining sleeve ports are single purpose ports in that they function only as intake ports or as exhaust ports, as the case may be.

What I claim as my invention is:

1. In a sleeve valve engine, sleeve valve intake and exhaust ports, cylinder intake and exhaust ports, and means effective when the sleeve and cylinder exhaust ports are in registration for conducting a portion of the exhaust gases to a point suitable for applying heat to the intake gases, said last named means including a cylinder passageway registering with the sleeve intake port at the period of the cycle mentioned.

2. In a sleeve valve engine, sleeve valve intake and exhaust ports, cylinder intake and exhaust ports, means effective when the sleeve and cylinder exhaust ports are in registration for conducting a portion of the exhaust gases to a point suitable for applying heat to the intake gases, said last named means including a cylinder passageway registering with the sleeve intake port at the period of the cycle mentioned, and means for conducting the exhaust gases from the point mentioned to mix with the

exhaust gases passing from the cylinder exhaust port.

3. In a sleeve valve engine, sleeve valve intake and exhaust ports, cylinder intake and exhaust ports, means effective when the sleeve and cylinder exhaust ports are in registration for conducting a portion of the exhaust gases to a point suitable for applying heat to the intake gases, said last named means including a cylinder passageway registering with the sleeve intake port at the period of the cycle mentioned, and means for conducting the exhaust gases from the point mentioned to mix with the exhaust gases passing from the cylinder exhaust port, the last named means including a cylinder passageway.

4. An engine comprising in combination, a cylinder provided with intake and exhaust passages, sleeve valve means having single purpose intake and exhaust passages cooperating with the cylinder passages, and means controlled by the sleeve valve means for exhausting the cylinder through the single purpose intake and exhaust passages of the sleeve valve means.

5. An engine comprising in combination, a cylinder provided with intake and exhaust passages, sleeve valve means having spaced single purpose intake and exhaust passages cooperating with the cylinder passages, and means controlled by the sleeve valve means for exhausting the cylinder through the said spaced single purpose intake and exhaust passages of the sleeve valve means.

6. An engine comprising in combination, a cylinder provided with intake and exhaust passages, sleeve valve means having intake and exhaust passages cooperating with the cylinder passages, said cylinder having a passageway in addition to the said cylinder passages controlled by the sleeve valve means for passage of exhaust gases from the cylinder through the said intake passage of the sleeve valve means.

7. An engine comprising in combination, a cylinder provided with intake and exhaust passages, sleeve valve means having intake and exhaust passages cooperating with the cylinder passages, and means controlled by the sleeve valve means for simultaneously exhausting the cylinder through the intake and exhaust passages of the sleeve valve means.

8. An engine comprising in combination, a cylinder provided with intake and exhaust passages, sleeve valve means having single purpose intake and exhaust passages cooperating with the cylinder passages, and means controlled by the sleeve valve means for exhausting the cylinder through the single purpose intake and exhaust passages of the sleeve valve means, said cylinder intake and exhaust passages extending substantially in opposite directions.

9. An engine comprising in combination, a cylinder provided with intake and exhaust passages, a single sleeve valve movably associated with the cylinder and provided with spaced single purpose intake and exhaust ports cooperating with the cylinder passages, and means for exhausting the cylinder through the said spaced single purpose intake and exhaust ports of the sleeve valve.

10. An engine comprising in combination, a cylinder provided with intake and exhaust passages, a single sleeve valve movably associated with the cylinder and provided with spaced single purpose intake and exhaust ports cooperating with the cylinder passages, and means for exhausting the cylinder through the said spaced single purpose intake and exhaust ports of the sleeve valve, said sleeve valve having a combined reciprocating and oscillating movement with respect to the cylinder axes.

11. An engine comprising in combination, a cylinder provided with intake and exhaust passages, a single sleeve valve movably associated with the cylinder and provided with spaced single purpose intake and exhaust ports cooperating with the cylinder passages, and means for exhausting the cylinder through the said spaced single purpose intake and exhaust ports of the sleeve valve, said sleeve valve having a combined reciprocating and oscillating movement with respect to the cylinder axes, the sleeve and cylinder axes being concentric.

12. An engine comprising in combination, a cylinder provided with intake and exhaust passages, sleeve valve means having intake and exhaust passages cooperating with the cylinder passages, means controlled by the sleeve valve means for exhausting the cylinder through the intake and exhaust passages of the sleeve valve means, and means conducting the gases exhausting through the intake passage of the sleeve valve means to apply heat to the intake gases.

13. An engine comprising in combination, a cylinder provided with intake and exhaust passages, sleeve valve means having spaced intake and exhaust passages cooperating with the cylinder passages, means controlled by the sleeve valve means for exhausting the cylinder through the intake and exhaust passages of the sleeve valve means, and means conducting the gases exhausting through the intake passage of the sleeve valve means to apply heat to the intake gases.

14. An engine comprising in combination, a cylinder provided with intake and exhaust passages, sleeve valve means having intake and exhaust passages cooperating with the cylinder passages, said cylinder having a passageway in addition to the said cylinder passages controlled by the sleeve

valve means for passage of exhaust gases from the cylinder through the said intake passage of the sleeve valve means, and means communicating with the said cylinder passageway for conducting the exhaust gases to apply heat to the intake gases.

15. An engine comprising in combination, a cylinder provided with intake and exhaust passages, sleeve valve means having intake and exhaust passages cooperating with the cylinder passages, means controlled by the sleeve valve means for exhausting the cylinder through the intake and exhaust passages of the sleeve valve means, said cylinder intake and exhaust passages extending substantially in opposite directions, and means conducting the gases exhausting through the intake passage of the sleeve valve means to apply heat to the intake gases.

20. 16. An engine comprising in combination, a cylinder provided with intake and exhaust passages, a single sleeve valve movably associated with the cylinder and provided with spaced intake and exhaust ports cooperating with the cylinder passages, means for exhausting the cylinder through the intake and exhaust ports of the sleeve valve, and means conducting the gases exhausting through the sleeve intake port to apply heat to the exhaust gases.

25. 17. An engine comprising in combination, a cylinder provided with intake and exhaust passages, a single sleeve valve movably associated with the cylinder and provided with spaced intake and exhaust ports cooperating with the cylinder passages, means for exhausting the cylinder through the intake and exhaust ports of the sleeve valve, said sleeve valve having a combined reciprocating and oscillating movement with respect to the cylinder axes, and means conducting the gases exhausting through the sleeve intake port to apply heat to the exhaust gases.

45. 18. An engine comprising in combination, a cylinder provided with intake and exhaust passages, a single sleeve valve movably associated with the cylinder and provided with spaced intake and exhaust ports cooperating with the cylinder passages, and means for exhausting the cylinder through the intake and exhaust ports of the sleeve valve, said sleeve valve having a combined reciprocating and oscillating movement with respect to the cylinder axes, the sleeve and cylinder axes being concentric, and means conducting the gases exhausting through the sleeve intake port to apply heat to the exhaust gases.

60. 19. An engine comprising in combination, a cylinder provided with intake and exhaust passages, sleeve valve means having circumferentially spaced single purpose intake and exhaust passages cooperating with the cylinder passages, and means controlled

by the sleeve valve means for simultaneously exhausting the cylinder through the said circumferentially spaced single purpose intake and exhaust passages of the sleeve valve means.

70. 20. An engine comprising in combination, a cylinder provided with intake and exhaust ports, sleeve valve means having single purpose intake and exhaust ports cooperating with the cylinder ports, means controlled by the sleeve valve means for exhausting the cylinder through the single purpose intake and exhaust ports of said sleeve valve means, and separate exhaust gas conducting means communicating with the sleeve valve single purpose port during a portion of the sleeve valve cycle when the sleeve and cylinder exhaust ports are in registration.

75. In witness whereof, I hereunto subscribe my name this 17th day of November, A. D. 1927.
